L. M. EDENS

MEDICINAL INSTRUMENT

Filed Aug. 10, 1927

UNITED STATES PATENT OFFICE.

LOUIS M. EDENS, OF CABOOL, MISSOURI.

MEDICINAL INSTRUMENT.

Application filed August 10, 1927. Serial No. 212,064.

This invention relates to a device for facilitating the introduction of medicinal powders and the like in the mouth and throat, the general object of the invention being to provide a hollow stem having a tongue depressor at one end thereof and a dosage receiver removably arranged at the other end, with means for inserting the nipple of a bulb in the receiver so that by depressing the bulb, the air from the bulb will cause the powder from the receiver to pass through the hollow stem and thus enter the mouth and throat of the patient.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a perspective view of the device.

Figure 2 is a sectional view thereof.

Figure 3 is a plan view, of the device showing the nipple of a bulb about to be inserted therein.

Figure 4 is a view of the holder and bulb.

Figure 5 is a perspective view of the holder.

In these views, 1 indicates a hollow stem which is formed with a tongue depressor 2 at one end thereof, this end of the hollow portion being shaped to form a nozzle 3. A holder 4 for powder and the like is adapted to be inserted in the other end of the stem, this holder being of rectangular shape, with a cup-shaped flange 5 at its outer end and its inner portion being cut away, as at 6, so that the powder or the like can be placed therein.

After the proper amount of powder has been placed in the holder, the holder is placed in the stem and then the nipple 7 of a bulb 8 is passed into the holder, the

flange 5 facilitating the entrance of the nipple therein. Then the bulb is depressed so that the air therefrom will cause the powder to pass through the device and be ejected against the walls of the mouth and throat of the patient. By providing the cut-away part 6 in the holder, the proper amount of powder can be placed therein and the flange 5 acts as a handle for inserting and withdrawing the holder from the tube.

With this device, the tongue can be held down by the part 2 and even though the patient should close his mouth, the powder can still be ejected through the stem. The device can be used with an ordinary atomizer bulb or any other kind of bulb.

As will be seen, this device can be readily taken apart and placed in a sterilizer, as it is entirely formed of metal and it can also be placed in the coat pocket or in a doctor's bag without fear of injuring it.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a tubular stem, a tongue depressor formed at one end of the stem, a tubular holder removably fitting in the other end of the stem, said holder having a cup-shaped flange at its outer end and its inner end being cut away to receive powder or the like.

2. A device of the class described comprising a tubular stem, a tubular holder removably fitting in one end of the stem, said holder having a cup-shaped flange at its outer end and its inner end being cut away to receive powder or the like and a bulb having a nipple thereon which is adapted to enter the holder so that the contents of the holder can be ejected from the device by depressing the bulb.

In testimony whereof I affix my signature.

LOUIS M. EDENS.
